UNITED STATES PATENT OFFICE

WILLIAM H. CLAYTON, OF PINE BLUFF, ARKANSAS

TELEPHONE TRANSMITTER

Application filed July 26, 1927. Serial No. 208,630.

This invention relates to certain novel and practical improvements in telephone transmitters, particularly of the type covered by my former Patent No. 1,529,343, granted 5 March 10, 1925, and primarily has for its object to improve the sensitiveness and clarity of the instrument, and also widen its range of use according to the particular service required thereof, at the same time adapting 10 the instrument for general telephony, as well as for any special uses, such as in radio circuits.

In addition to these general objects the invention contemplates certain improvements 15 in the manner of mounting and co-ordinating the vibrating parts of the instrument, thereby to obtain a refinement in the phonetic value thereof, at the same time having in view a construction which is well adapted for production manufacture at low 20 cost, and which makes an instrument which is thoroughly practical for use in any and all positions and for any purpose to which a sound transmitting device may be utilized.

With these and other objects in view which will more readily appear to those familiar 25 with the art as the nature of the invention is better understood, the same consists in the novel construction and coordination of elements more particularly described herein, 30 illustrated in the drawings, and made the subject-matter of the claims.

The essentials of the invention necessarily 35 are susceptible of a wide range of modification without departing from the spirit or scope thereof, but for illustrative purposes a practical embodiment of the features of the improvement are shown in the accompanying drawings, in which:—

Figure 1 is a side elevation, with the casting in section, of a sound transmitting instrument, termed herein telephone transmitter, having the parts assembled in the 40 manner contemplated.

Figure 2 is a plan view of the instrument with the balanced contact carriers and their supports removed.

Figure 3 is a similar view showing the instrument with the balanced contact carriers

and their supports in position over the primary or universal electrode bar.

Figure 4 is a vertical sectional view of the working parts of the instrument.

Figure 5 is a skeletonized perspective view 55 of the coordinated active elements of the instrument.

Figures 6, 7 and 8 are diagrammatic views 60 illustrating the different electrical circuit arrangements that may be employed with the instrument.

The working parts of the instrument are housed in a suitable casing or boxing designated generally by the letter C, the same including the usual front panel or plate which will be termed herein the base, upon which the working parts of the instrument may conveniently be mounted and which is provided with the usual opening 2 therein for receiving the sound waves. Over this base, at its inner side, is resiliently supported the primary 65 vibrating member designated by the reference numeral 3 and usually termed the diaphragm. A feature of practical importance is to allow this diaphragm or vibrating member to have a perfectly free and full motion.

To that end the present invention proposes to provide the diaphragm at opposite sides thereof, which in the ordinary position, as shown in the drawings, would be 70 the upper and lower sides of the diaphragm, with the bowed or bent spring feet 4 which lightly bear against the inner side of the instrument base, and by reason of their 75 bowed or bent formation serve to yieldingly hold the diaphragm spaced from the instrument base a sufficient distance to permit it freely to have a full motion as it receives and responds to the sound vibrations. This manner of mounting the diaphragm permits 80 the same to be balanced in a way presently 85 to be described.

As a feature of structure in connection 90 with the mounting of the diaphragm it will be noted that the preferable form shown is a diaphragm body of a cupped or box-like formation having the peripheral stiffening flange 5 extending about its edges, and this diaphragm also preferably is rectangular in shape and fits over a correspondingly shaped 100

- boss or collar 6 which projects over the inner side of the instrument base. This detail is of practical importance because it is a well recognized fact that as the sound vibrations in the air are more in the nature of a tension than an actual movement, any obstruction causing the vibrations to move in an indirect path rather than in a straight line tends to cause movement. Because of that fact it is preferable in carrying out the invention to have a part of the casing represented by the boss or collar 6 projecting into the cavity or depressed side of the vibrating member or diaphragm.
- 5 To provide for a very delicate and balanced mounting of the diaphragm or primary vibrating member 3 of the instrument, and to provide for mechanically transmitting the vibrations of the diaphragm to the electrical circuit or circuits forming a part of the instrument, a novel system of levers is preferably employed. This leverage system includes primarily a pair of tension levers 7—7 disposed respectively at opposite sides of the 10 diaphragm 3, and constructed to have an engagement with the diaphragm under slight tension so as to be sensitive to all vibrations thereof and to become in effect a part of the diaphragm so as to follow its movement. In 15 the preferred embodiment shown in the drawings these tension levers 7 may be and are preferably cut as at 7^a to form light springs having a fixed attachment as at 8 or on a cleat or equivalent point of support 9 on the instrument base, and at its opposite or unattached end each tension lever 7 is provided with an engaging hook 10 which has a slight tensional engagement with a bearing step 11 or equivalent element projecting from 20 the side of the diaphragm.
- 25 The opposite tension levers 7, which are correlated to the diaphragm 3 in the manner described, transfer vibrations received from the diaphragm to the opposite relatively long transfer levers 12. These transfer levers are also preferably cut as at 12^a to form light springs having a fixed point of attachment, as at 13, in or on a cleat 14 on the inner side of the instrument base, and the free end of 30 each of said relatively long transfer levers is provided with an inwardly extending engaging hook or equivalent element 15 which engages over and upon one of the tensioning levers 7 at a point intermediate the ends of 35 the latter, and preferably between the center of the latter and the fixed point of attachment 8 thereof. This provides for a great reduction of the movement of the diaphragm and the lever 7, which reduced movement is 40 transferred by the said transfer levers 12 to the primary electrode bar 16 which spans the space between and rigidly connects as at 17 with the opposite transfer levers 12. It will now be observed that the tensionally interengaged levers 7 and 12 are opposed in 45

their action to what may now be termed the seating springs 4 for the diaphragm and the combined strength of the said levers 7 and 12 preferably is so regulated as to be substantially equivalent to the strength or 50 spring-action of the seating springs 4 to provide what may be characterized as a balanced suspension for the diaphragm in serving to overcome the inertia thereof in both directions, as well as to clearly absorb the momentum of the diaphragm in both directions when acted upon by sound waves. By reason of thus balancing both the inertia and 55 momentum of the primary vibrating member or diaphragm of the transmitter, preferably by springs that have a higher vibrating effect the effectiveness of the instrument is greatly increased. Primarily the tension on the said levers 7 and 12 pressing on the vibrating member is sufficient to compel the 60 said levers to follow its movement accurately, and by varying this tension and the strength of the springs supporting or seating the said vibrating member or diaphragm the sensitivity of the instrument both as to loudness 65 and pitch can be widely varied; also the loudness and pitch of the instrument can be varied by altering the weight and size of the vibrating member or diaphragm itself and the relative difference of weight and of 70 size.

The primary electrode bar, by reason of its function of being common to and cooperating with one or more balanced electrode carriers which are parts of the electrical 75 transmitting circuit, may also be termed or referred to as a universal electrode bar. This bar may conveniently be in the form of a channeled piece of sheet metal or other suitable material and is designed to have 80 seated therein a plurality of carbon or equivalent conducting electrodes 18. These electrodes 18 are preferably in the form of strips of carbon or equivalent materials seated in pockets or sockets provided for by the primary or universal electrode bar 16, and are of any desired length according to the number of these electrodes it is desired for the instrument to carry. Between and about the 85 said electrodes is interposed suitable insulating separators 19 to insulate them from their holder and from each other so as to prevent short-circuiting, and to compel the closing of the electrical circuit between one or more carbon contact elements 20 which are held in light contact with one or more of the electrodes 18.

Considering each carbon or equivalent contact element 20 as a separate and independent unit of construction it will be observed that 90 an important feature of the present invention resides in the mounting of these contact elements. Referring particularly to the drawings, it will be seen that each carbon contact element 20 is preferably fitted to or in one end 95 of

of what is termed herein a balanced contact carrier, designated generally by the reference number 21. This contact carrier is shown in the form of a lever having a pivotal support or mounting at its center of gravity, as at 22, on a supporting arm 23, one end of which has a fixed point of attachment to a holding block 24 by being detachably inserted in a slit 25 in said block or in any equivalent or desired manner. By reason of mounting each contact carrier 21 on a pivot at its center of gravity, the contacting carbons 20 and 18 are relieved of practically all pressure, and is uniform in any position of instrument, and in effect only the inertia of the contact carrier 21 is encountered by the vibrating element or carbon 18. A very light holding spring 26, carried by each supporting arm 23 and at its free end 27 bearing on the carrier 21 between the pivot 22 and the contact 20, is employed for the purpose merely to hold the contact carrier 21 against displacement from its operative position, and to furnish an initial tension that maintains the elements 20 and 18 in operative relation. It is by reason of this particular construction that the instrument is given the higher vibrating period and its effectiveness much increased. This is due to the fact that the contact element 20 is so held against the electrode 18 which is actuated by the diaphragm, that the inertia of the carrier 21 for the contact element 20 provides practically the only resistance to the variant motion of the electrode 18 which is effective to correspondingly vary the current.

To illustrate the wide application of the invention the three diagrammatic Figures 6, 7 and 8 are referred to. As indicated in Fig. 6 a single one of the contact carriers 21 and its contact 22 may be used in connection with a single one of the diaphragm actuated electrodes 20, and the instrument is constructed to permit of using a single one of the said contact carriers and its contact element or a pair of such contact carriers and their elements or more than one pair according to the voltage and amperage of the current to be used and according to the particular use of the instrument. For instance, referring first to Fig. 6 it will be observed that the wiring may be conveniently made through suitable binding terminals 28 and 29 fitted to the holding block 24 which is of wood or equivalent insulated material, one of the contact carriers with its support having a wire connection *a* with one binding terminal 28, and another wire connection *b* may be made with the other binding terminal 29 and directly with the diaphragm actuated electrode 18 which has a contacting engagement with the contact element 20 of the contact carrier. In this exemplification of the invention a single one only of the contact carriers and its contact element is used and the electrical circuit is completed through the contacting conduct-

ing elements 18 and 20. These binding terminals are respectively connected by wires *c* and *d* to a receiver R and a source of electrical energy, as a battery B.

As shown in Fig. 7 of the drawings the illustration is of the use of a pair of the contact carriers 21 and their contact elements 20. In this embodiment of the invention the contact elements are paired so as to be included on opposite sides of the same electrical circuit, one of the contact carriers with its support having the wire connection *a* with one wire terminal 28 and the other contact carrier and its support having the wire connection *b* with the other binding terminal 29. In this form of the invention the electrode 18 acts as a conducting bridging element between the two contact elements 20.

As shown in Figure 8 of the drawings a number of the paired carbon contact elements 20 and their associated parts are shown arranged over the electrode bar which carries the plurality of separate and independently insulated electrodes 18. In this figure of the drawings where a plurality of the contact elements are employed a multiple or parallel circuit may be employed in connection with the telephone circuit, and to show an alternative arrangement Fig. 3 of the drawings illustrates a series circuit for a plurality of the carbon contact elements.

It will now be observed that an important feature of the present invention resides in the capability and adaptability of the instrument being used with one of the contact elements 20, with a pair of such elements or with more than a pair of such elements. Where a single one of the contact elements or a single pair thereof may be employed, the instrument will work on a low voltage and small current, and for higher voltages or larger currents the contact elements and their parts can be multiplied to any desired extent, thus providing an instrument which will meet any requirement of service that may arise in practice. Furthermore, the novel construction and arrangement of parts described provide an instrument which may be successfully operated with from one to three milliamperes of current as compared with the much heavier current required for use with the telephone transmitters in general use. Also, the novel construction and arrangement of parts described provide a transmitting instrument which is sensitive to all distances, within a reasonable range, thus adapting the instrument for all kinds of service whether in houses, factories or other public places.

I claim:

1. A telephone transmitter including a diaphragm balanced as to motion and its effects between opposing tensions, a primary electrode actuated by the diaphragm, and a contact element included in the electrical circuit and so held against the electrode that its iner-

- tia provides the only effective resistance to the varying motion of the electrode.
2. A telephone transmitter including a diaphragm balanced as to motion and its effects between opposing tensions, an electrode actuated by the diaphragm, and a contact carrier included in the electrical circuit and carrying a contact element held against the electrode, the weight only of said carrier and contact 10 providing the only effective resistance to the motions of the electrode.
3. A telephone transmitter including a diaphragm balanced as to motion and its effects between opposing tensions, an electrode actuated by the diaphragm, a balanced contact carrier included in the electrical circuit carrying a contact element contacting with the electrode, said contact carrier and its contact element being so arranged that the inertia 15 thereof provides the only effective resistance to the varying motion of the electrode.
4. A telephone transmitter including a diaphragm, a system of motion reducing levers actuated by the diaphragm and carrying an 20 electrode, and a contact element so held against the electrode that its inertia provides the only effective resistance to the varying motion of the electrode.
5. A telephone transmitter including a dia- 25 phragm, a system of motion reducing levers actuated by the diaphragm and carrying an electrode, and a spring tensioned contact element held against the electrode, the inertia of said element and its support constituting the 30 resistance to the motions of the electrode.
6. A telephone transmitter including a dia- 35 phragm balanced as to motion and its effects between opposing tensions, a system of motion reducing levers actuated by the dia- 40 phragm and carrying an electrode, and a spring tensioned contact element so mounted that its inertia provides the effective resistance to the varying motion of the electrode.
7. A telephone transmitter including a dia- 45 phragm, an electrode actuated by the dia- 50 phragm, a spring tensioned pivotally mounted contact carrier carrying a contact element engaging the electrode, the inertia of said carrier and contact element constituting the resistance to the motions of the electrode.
8. A telephone transmitter including a dia- 55 phragm, an electrode actuated by the dia- 60 phragm, a spring tensioned balanced pivotally mounted contact carrier carrying a contact element engaging the electrode, the inertia of said carrier and contact element constituting the resistance to the motions of the electrode.
9. A telephone transmitter including a dia- 65 phragm, an electrode actuated by the dia- 70 phragm, and a contact carrier having a pivot- 75 al support at its center of gravity and carrying the contact element engaging the elec- 80 trode, the inertia of said carrier and contact 85 element constituting the resistance to the motions of the electrode.
10. A telephone transmitter including a diaphragm, an electrode actuated by the dia- 90 phragm, and a spring tensioned contact car- 95 rier pivotally mounted at its center of gravity and carrying the contact element engaging the electrode, the inertia of said carrier and contact element constituting the resistance to the motions of the electrode. 100
11. A telephone transmitter including a dia- 105 phragm, an electrode actuated by the dia- 110 phragm, and a plurality of contact elements included in the electrical circuit and held against the electrode, the inertia of the contact elements and their supports constituting the resistance to the motions of the electrode. 115
12. A telephone transmitter including a dia- 120 phragm, a plurality of electrodes actuated by the diaphragm and insulated one from the other, and a plurality of contact elements in- 125 cluded in the electrical circuit and respectively contacting with separate electrodes, the inertia of the contact elements and their supports constituting the resistance to the motions of the electrode. 130
13. A telephone transmitter including a dia- 135 phragm balanced as to motion and its effects between opposing tensions, a system of motion reducing levers actuated by the dia- 140 phragm and carrying an electrode holder, a plurality of electrodes carried by said holder and insulated therefrom and from each other, and a plurality of balanced contact elements included in the electrical circuit and respec- 145 tively held against separate electrodes. 150
14. A transmitting instrument including a dia- 155 phragm, a system of motion reducing levers actuated by the diaphragm and carrying a plurality of independently insulated electrodes, and a plurality of pairs of contact elements, each pair of contact elements re- 160 spectively engaging a single one of the said electrodes, and each of said pairs of contacts being balanced whereby the inertia of the same and their supports constitute the resistance to the motions of the electrode engaged thereby. 165
15. A transmitting instrument including a dia- 170 phragm, a system of motion reducing levers actuated by the diaphragm and carrying a plurality of independently insulated electrodes, and a plurality of movable and re- 175 placeable contact elements, each respectively adapted to engage one of the electrodes, each contact element and its support having a balanced mounting so that the inertia thereof will constitute the resistance to the motions of the electrode. 180
16. A telephone transmitter having a dia- 185 phragm balanced as to its inertia and momentum. 190
17. A telephone transmitter including a dia- 195 phragm having seating springs at one side and a system of motion transmitting spring 200

elements having a tensioning engagement with the diaphragm in opposition to the seating spring to provide for a balancing of the diaphragm.

5 18. A telephone transmitter including a diaphragm having seating springs at one side, a system of motion transmitting springs having a tensioning connection with the diaphragm and carrying an electrode, and a contact element included in the electrical circuit and held against the electrode.

10 In testimony whereof I hereunto affix my signature.
